UNITED STATES PATENT OFFICE.

ARCHIE NOEL JETTE, OF ANACONDA, MONTANA.

REVERBERATORY FURNACE.

Application filed December 27, 1920. Serial No. 433,380.

To all whom it may concern:

Be it known that I, ARCHIE NOEL JETTE, a citizen of the United States, residing at Anaconda, in the county of Deerlodge and 5 State of Montana, have invented certain new and useful Improvements in Reverberatory Furnaces, of which the following is a specification.

The present invention relates to furnaces 10 for the treatment of ores and more particularly to reverberatory furnaces.

It is the general experience with reverberatory furnaces that those portions of the charge-feeding pipes which are in contact 15 with the furnace proper burn out rapidly because of the intense heat to which they are subjected, making frequent repairs and replacement necessary.

It is the main object of this invention to 20 provide a construction whereby the necessity of repairs and replacements is obviated as far as possible and whereby, when repairs are necessary, they can be quickly and cheaply made.

25 For a full understanding of the invention reference is had to the accompanying drawings in which—

Fig. 1 is a transverse section of a furnace embodying the invention,

30 Fig. 2 is a fragmentary sectional view on a larger scale showing a detail; and

Figs. 3 and 4 are plan view and elevation of a part forming an important part of the invention.

35 Having reference to Fig. 1, 10 is the bottom, 11 the side wall and 12 the roof of a usual type of reverberatory furnace, held together against the tremendous influence of heat by side stays 13 interconnected by 40 stress rods or bars 14.

Above the furnace is a beam construction 15 affording a support for the ore-feeding system, only a part of the said beam construction being shown.

45 A plurality of feed pipes are in practice connected with the furnace throughout its length and at both sides thereof. Each pipe includes a casting 21 having a nipple 20 extending through the roof and a nipple 22, a 50 main pipe 26 leading from a hopper 27 and

connected to the nipple 22 by means of a sleeve 25. The sleeve 25 reinforced by a collar 24 loosely surrounds the pipe 26 and the nipple 22 and rests upon a collar 23 on the casting 21.

The nipple 20 is surrounded by a thimble 28 containing a coil 29 which has an inlet and an outlet 30 and 31 respectively. At its upper end the thimble 28 has a flange 32 forming a seat. The upper portion of the 60 roof is provided with a recess to receive the thimble, the flange 32 resting on the upper surface of the roof.

The nipple may be of cast iron or other suitable heat-resisting material. The inlet 65 and outlet 30, 31 may be connected with a circulating system. A cooling fluid passing through the coil 29 reduces the temperature about the nipple 20 and the casting 28, generally, so that the life of usefulness of the 70 casting is many times longer than it ordinarily would be. It should be understood that the intense heat ordinarily causes considerable stress and movement of the affected parts. These extreme stresses are avoided 75 since the temperature at which the heat is conducted off as fast as it is transmitted to the nipple 20 is relatively low.

In order, however, to reduce and practically eliminate the reaction of the casting 21 80 upon the remaining part of the pipe, I may advantageously provide the sleeve 25. Movement of the casting 21 will cause merely a sliding of the sleeve 25 over pipe 26.

I claim:

1. In a furnace of the type described, the combination with the roof, of a feed pipe extending therethrough and a solid metallic body containing a cooling coil surrounding the pipe.

2. Construction according to claim 1 including an expansible section in the feed pipe adjacent the roof.

3. In a furnace of the type described, the combination with the roof, of a feed pipe 95 extending through the roof including an expansible section adjacent the roof.

4. In a furnace of the type described, the combination with the roof, of a feed conduit comprising a nipple passing through the 100

2
roof, a pipe and a sleeve passing over and interconnecting the pipe and the nipple providing an expansible connection.

5. In a furnace of the type described, the combination with the roof, of a feed conduit comprising a nipple extending through the roof, a feed pipe, a sleeve passing over and interconnecting the pipe and the nipple, a metallic body seated in the roof and contacting with the nipple and a cooling coil 10 embedded in the body.

In testimony whereof, I affix my signature.

ARCHIE NOEL JETTE.
